UNITED STATES PATENT OFFICE.

HAROLD J. BELL, OF WOODBURY, NEW JERSEY, ASSIGNOR TO THE WELS-BACH INCANDESCENT GAS LIGHT COMPANY, OF NEW JERSEY.

INCANDESCENT GAS-BURNER.

SPECIFICATION forming part of Letters Patent No. 390,056, dated September 25, 1888.

Application filed March 21, 1888. Serial No. 267,985. (No model.)

To all whom it may concern:

Be it known that I, HAROLD J. BELL, a citizen of the United States, residing at Woodbury, in the county of Gloucester and State 5 of New Jersey, have invented new and useful Improvements in Incandescent Gas-Lamps, of which the following is a specification.

My invention relates to that class of lamps which are particularly adapted for the consumption of non-carbureted gas when used with an incandescing device such as is known as a "mantle" in the Welsbach system of incandescent gas-lighting.

The lamps now used in the Welsbach system comprise an atmospheric gas-burner and a chimney inclosing a mantle of refractory incandescent material suspended above the burner. By my present invention I am enabled to dispense with the ordinary atmospheric gas-burner and the chimney, though a chimney or globe may be employed, if preferred.

My invention consists in the combination, with a gas-burner having a top provided with a number of fine perforations or gas-exits, of a laterally-perforated air-tube surrounding the upper portion of the burner at a suitable distance therefrom, and a perforated cup that surrounds the air-tube and receives and protects the lower end of the mantle, the perforations in the said cup and air-tube being so arranged that currents of air will be caused to pass upward along both the inner and outer surfaces of the mantle, thereby effecting a perfect combustion of gas with uniform incandescence of the mantle and enabling the chimney to be dispensed with, if desired.

In the annexed drawings, illustrating the invention, Figure 1 is a sectional elevation of an incandescent gas lamp and burner embodying my improvements. Fig. 2 is a top view of the same. Fig. 3 is a perspective view of the burner-tube, perforated air-tube, and perforated cup connected together, but with the burner removed.

The numeral 1 designates a portion of a gas-supply pipe, 2 a burner-tube, and 3 the burner proper, which is provided with a flat top having a number of fine perforations or gas-exits, 4, by which the escaping gas is divided into a

number of fine currents. The lower portion of the burner-tube 2 is closely surrounded by a thin metal tube, 5, which is expanded or enlarged near the upper end of the burner-tube and surrounds the burner 3 at a suitable distance. The enlarged portion of the tube 5, surrounding the burner 3, is open at the top and provided with lateral air-passages 6, for the inlet of air to the space immediately surrounding the burner. An open-topped or 55 cup-shaped mantle-protector, 7, provided with central perforations, 8, is supported on and surrounds the upper portion of the perforated air-tube 5, as shown. The cup or protector 7 extends slightly above the upper end of the 60 air-tube 5, and its perforations 8 are preferably of greater number and larger combined area than the perforations 6 of the air-tube, thus serving to admit sufficient air for both the outer and inner surfaces of the mantle. The 65 perforations 8 are preferably vertically elongated and extend above the circular perforations 6 from a line that is about on a level with the center of said circular perforations. A portion of the air admitted through the 70 elongated and more numerous perforations 8 is thus caused to pass through the perforations 6 to the interior of the mantle, while the surplus ascends through the cup 7 to the outer mantle-surface.

The mantle 9 is suspended, as usual, from a ring, 10, on the upper end of a rod, 11, that is adjustably supported by means of a screw, 12, in a lug or stud, 13, projecting laterally from the burner-tube. The lower end of the mantle 85 is received in the cup or protector 7 and surrounds the upper portion of the air-tube 5 above its lateral air-inlets 6, care being taken to adjust the mantle and its support in such a manner that the lower edge of the mantle will 90 not cover or obstruct the air-inlets.

A gallery, 14, may be provided for supporting a globe or chimney, 15; but this is not essential, as the arrangement and construction of the burner, air-tube, and perforated mantle-protector in the manner above-described are 95 amply sufficient to secure an equal distribution of air on the outer and inner surfaces of the mantle, with perfect combustion of the gas and such degree of incandescence as to 100

afford a steady and brilliant light without the use of a chimney.

What I claim as my invention is—

1. In an incandescent gas-lamp, the combination, with a gas-burner having a top provided with gas-exits, of a laterally-perforated air-tube surrounding the upper portion of the burner at a sufficient distance therefrom to insure perfect combustion, and a perforated cup surrounding the air-tube to receive and protect the lower end of the mantle, whereby air is equally distributed on both the inner and outer mantle-surfaces, substantially as described.
2. In an incandescent gas-lamp, the combination of a gas-burner having a number of gas-exits, an air-tube surrounding said gas-burner and provided with lateral air-inlets, and a cup-shaped mantle-protector surrounding the air-tube and provided with lateral air-

inlets that extend above the air-inlets of the air-tube, whereby the air is distributed on both surfaces of the mantle, substantially as described.

3. In an incandescent gas-lamp, the combination of the burner-tube 2, the burner 3, provided at its top with gas exits 4, the air-tube 5, having lateral air-inlets 6, surrounding the burner, the cup 7, surrounding the air-tube and provided with lateral air-inlets 8, and the mantle 9, suspended above the burner, with its lower edge inclosed in the cup 7 above the inlets of the air-tube, substantially as described.

In testimony whereof I affix my signature in presence of two witnesses.

HAROLD J. BELL.
